UNITED STATES PATENT OFFICE

JOE H. GLENN, JR., AND BERT L. BENNETT, OF WINSTON-SALEM, NORTH CAROLINA,
ASSIGNORS OF ONE-THIRD TO HORACE M. DU BOSE, JR., AND ROBERT C. VAUGHN,
BOTH OF WINSTON-SALEM, NORTH CAROLINA

DESIGN FOR A FILLING STATION

Application filed July 24, 1930. Serial No. 36,463. Term of patent 14 years.

To all whom it may concern:

Be it known that we, JOE H. GLENN, Jr., and BERT L. BENNETT, citizens of the United States, residing at Winston-Salem, in the county of Forsyth and State of North Carolina, have invented a new, original, and ornamental Design for Filling Stations, of which the following is a specification, reference being had to the accompanying drawing wherein

Figure 1 is a front view of a filling station embodying our design.

Fig. 2 is a rear view thereof, and
Fig. 3 is an end view thereof.

We claim:

The ornamental design for a filling station as shown.

Signed at Winston-Salem, North Carolina, this 22nd day of July, 1930.

JOE H. GLENN, JR.
BERT L. BENNETT.
